UNITED STATES PATENT OFFICE.

SAMUEL R. MUNSON, OF NEW BRITAIN, CONNECTICUT, ASSIGNOR TO CHARLES F. SMITH AND GEORGE M. LANDERS, OF NEW BRITAIN, CONNECTICUT.

MIXING VESSEL.

SPECIFICATION forming part of Letters Patent No. 729,884, dated June 2, 1903.

Application filed April 4, 1903. Serial No. 151,172. (No model.)

To all whom it may concern:

Be it known that I, SAMUEL R. MUNSON, a citizen of the United States, residing at New Britain, in the county of Hartford and State of Connecticut, have invented certain new and useful Improvements in Mixing Vessels, of which the following is a specification.

My invention relates to improvements in mixing vessels; and the object of my invention is to provide simple and efficient means for firmly clamping the vessel to a table-like support.

In the accompanying drawings, Figure 1 is a front elevation of my mixing vessel, together with a portion of a table to which it is attached. Fig. 2 is a reverse plan showing the bottom of my vessel. Fig. 3 is a sectional side elevation of the lower part of the said vessel and a portion of a table.

20 A designates a vessel which is round in plan view and which I have shown shallow for convenience of illustration, but which may be of any desired height. My improvements relate solely to the lower part of the vessel and the clamp for use therewith. The improvement is particularly useful in that class of mixing vessels which are used in connection with an agitator that is driven by a crank—as, for example, dough-mixers. Such 25 vessels are often made of thin material, and it is difficult to firmly secure them to a table so that the metal will not buckle or bend under the strain of the crank-operated mechanism.

30 Across the bottom of the vessel A, at the middle portion, I secure a socket 4 of a rectangular form in cross-section (see broken lines in Fig. 1) and open at both ends, the said ends terminating near the outer edge of the bottom, as shown. This socket is adapted to receive the tenon or tongue 5 of the clamp 6, which extends nearly half-way through the said socket. The said socket also serves to stiffen or reinforce the bottom of the vessel.

40 On diametrically opposite points in a line at right angles to the length of the socket I secure to the under side of the bottom, near

the outer edge, the two bosses or projections 7, the depth of which is a little in excess of the height or depth of the socket 4, whereby 45 when the tenon 5 is inserted in the said socket and the vessel clamped to the table B by tightening the screw 8 of the clamp 6 the vessel will be slightly tilted toward the front and rest upon three points—viz., the two 50 bosses and forward end of the socket—as shown in Fig. 3. It is immaterial which end of the socket is presented to the front edge of the table, as the tenon can be inserted into either end, and that end, whichever it may be, will 55 be forced down to a firm bearing at the front edge of the table. This throws substantially all of the strain on points near the outer edge where the bottom is the stiffest by reason of its being reinforced by the side of the vessel. 60

I claim as my improvement—

1. A mixing vessel, having the clamp-receiving socket extending along the under side of the bottom from its edge inwardly and the two projections on the bottom arranged in a 65 line transversely to the length of the said socket, substantially as described.

2. In a mixing vessel, the combination of the bottom of the vessel having the clamp-receiving socket and two projections, with a 70 clamp having a tenon adapted to be received in the said socket.

3. In a mixing vessel, the combination of the bottom of the vessel with the double-ended clamp-receiving socket extending across the 75 said bottom, the two projections on opposite sides of the said socket, and the clamp having a tenon fitted to the said socket.

4. In a mixing vessel, the combination of the bottom of the vessel having the clamp-receiving socket and the two projections on opposite sides thereof, with a clamp having a tenon fitted to the said socket, the said two projections being slightly deeper than the depth of the said socket.

SAMUEL R. MUNSON.
